UNITED STATES PATENT OFFICE.

BENJAMIN THOMAS WEBB, OF BEAUFORT, NORTH CAROLINA.

STEAM-ENGINE.

SPECIFICATION forming part of Letters Patent No. 339,506, dated April 6, 1886.

Application filed November 21, 1885. Serial No. 183,518. (No model.)

To all whom it may concern:

Be it known that I, BENJAMIN THOMAS WEBB, of Beaufort, in the county of Carteret and State of North Carolina, have invented 5 a new and useful Improvement in Steam-Engines, of which the following is a specification, reference being had to the annexed drawings, forming a part thereof, in which—

Figure 1 is a side elevation, partly in section, of my improved engine. Fig. 2 is a vertical transverse section taken on line $x-x$ in Fig. 1. Fig. 3 is a vertical transverse section taken on line $y-y$ in Fig. 1.

Similar letters of reference indicate corresponding parts in the different figures.

The object of my invention is to provide means for converting the reciprocating motion of the engine-piston into rotary motion without the use of a crank or of racks and pinions; 20 also, to avoid the loss of power common to the use of the crank by employing a uniform leverage throughout the entire stroke of the engine.

My invention consists in a friction-wheel secured on the main shaft of the engine, and in 25 a yoke carried by the piston-rod, arranged to alternately engage opposite sides of the friction-wheel, and in means for bringing the yoke into engagement with one or the other of the 30 sides of the friction-wheel, according to the movements of the piston.

The cylinder A is of the usual description, provided with ports $a-a$ and b , a valve-chest, B, and slide-valve C, of the usual description. 35 The piston-rod D slides through a stuffing-box, E, in the head of the cylinder A, and is secured to a standard, F, rising from the cross-head G, which slides in ways H, secured on the bed of the engine. The cross-head G carries a yoke, I, formed of the parallel side pieces, J, and the connecting end pieces, $c-c'$, the end piece c' of the yoke I being pivoted on a stud, e, projecting from the standard F, so as to permit of a slight vertical movement 40 of the yoke I. Upon the main shaft K is secured a friction-wheel, L, which is of sufficient diameter to nearly fill the space between the side bars, J J', of the yoke I, so that very little movement of the yoke I is required to 45 bring either of its side bars, J J', into frictional contact with the surface of the friction-

wheel L. Standards M, secured to the base of the engine, support the journal-boxes f of the main shaft K, and also support above and below the friction-wheel L and the yoke I the steam-cylinders N N', whose ends are opened toward the shaft K, and each cylinder N N' contains a piston, O, carrying a yoke, P, in which is journaled a roller, Q, which is capable of being pressed by steam entering the cylinder against the side of the yoke I. The cylinder N above the yoke I communicates with the forward end of the cylinder A by the pipe g, and the cylinder N' communicates with the back end of the cylinder A by the pipe g'. 60 The pipes g and g' are provided with valves h and h', and a pipe, i, communicating with the valve h of the upper pipe, g, is connected with the pipe g' upon the main-cylinder side of the valve h', and the valve h' is connected by a pipe, i', with the pipe g upon the main-cylinder side of the valve h. The valves h and h' are each provided with a plug, j, which is capable of closing either one of the openings of the valve. When the valves h and h' are 65 arranged to close the openings thereof leading to the cross-pipes i and i', steam entering the forward end of the cylinder will pass through the pipe g and force out the piston O from the cylinder N, and cause the roller Q to bear 70 upon the top of the yoke I, and when steam is admitted to the opposite end of the cylinder A a pressure will be exerted upon the piston O of the cylinder N', forcing the roller Q against the under side of the yoke I, bringing 75 the lower bar, J', into frictional contact with the friction-wheel L.

The standard F is prolonged above the yoke I to form a tappet, R, which is bored transversely to receive the valve-rod S, having 80 near the opposite ends the collars k k', which are engaged alternately by the tappet R. The valve-rod S is connected through a lever, T, with the stem l of the slide-valve C.

When steam is admitted to the forward end 95 of the cylinder A, it not only acts upon the main piston of the engine to force it back, but it simultaneously acts upon the piston O, contained by the cylinder N, so that as the piston of the main cylinder tends to draw the 100 yoke I backward the piston O, through the roller Q, presses the bar J into frictional con-

tact with the upper surface of the friction-wheel L, and causes the friction-wheel L to rotate. The greater the steam-pressure in the main cylinder the greater will be the pressure upon the bar J to bring it into contact with the friction-wheel L.

When the piston of the main cylinder has about completed its rearward stroke, the tappet R engages the collar k' on the valve-rod S and shifts the slide-valve C, so that steam is exhausted from the forward end of the cylinder and admitted to the rear end of the cylinder. This shifts the piston O in the cylinder N and causes a pressure to be exerted upon the piston O of the cylinder N', bringing the bar J' into frictional contact with the friction-wheel L, and at the same time releasing the bar J, so that as the piston moves outward the rotary movement of the friction-wheel L is continued in the same direction as before.

When the piston of the main cylinder completes its forward stroke, the valve C is again shifted by the engagement of the tappet R with the collar k on the valve-rod S, and steam is again admitted to the forward end of the cylinder A, while it is allowed to exhaust from the rear end.

To reverse the motion of the friction-wheel L and the main shaft K, the plugs of the valves h h' are turned so as to close the pipes g g' upon the main-cylinder side of each valve, as indicated in dotted lines in Fig. 1. This will result in conducting steam from the rear end of the cylinder A to the upper cylinder, N, through the pipe g', cross-pipe i, and pipe g, and steam will be conducted from the forward end of the main cylinder A through the pipe g, cross-pipe i', and that portion of the pipe g' lying between the valve h' and the cylinder N', so that when the piston in the main cylinder moves backward the under surface of the friction-wheel L will be engaged by the bar J', and the motion of the friction-wheel and main shaft will be the reverse of that first described.

It will be observed that only a very slight movement of the yoke I is required to insure the engagement or disengagement of the bars J J' and the friction-wheel L.

To facilitate the reversing of the engine, the plugs of the valves h h' may be connected together or provided with suitable means for operating them simultaneously.

Although I have described a means for operating the slide-valve C, I do not limit or confine myself to this particular means, as other existing well-known devices may be employed for the same purpose.

It is obvious that either of the steam-cylinders may be made double-acting and provided with a prolonged piston-rod arranged to carry both of the rollers Q, when the pipes g g' would be connected with opposite ends of that cylinder, and one of the cylinders might be dispensed with.

Having thus described my invention, what I claim as new, and desire to secure by Letters Patent, is—

1. In a steam-engine, the combination, with the main cylinder, piston, and piston-rod of the engine, of a yoke embracing a friction-wheel on the main shaft of the engine, and one or more steam-actuated pistons for bringing the yoke into engagement with the sides of the friction-wheel, substantially as herein specified.

2. The combination, with the steam-cylinder A and its piston and piston-rod, of a yoke, I, having parallel side bars, J J', and connected movably with the piston-rod, steam-cylinders N N', pistons O, and friction-rollers Q, and steam-pipes g g', connecting the cylinders N N' with opposite ends of the main cylinder A, as herein specified.

3. The combination, with the cylinders N N' and steam-pipes g g', leading thereto, of cross-pipes i i' and valves h h', substantially as herein shown and described.

4. In a steam-engine, the combination of the main cylinder A and its piston and piston-rod, the yoke I, friction-wheel L, cylinders N N', pistons O, and friction-rollers Q, the pipes g g', cross-pipes i i', and the valves h h', as herein specified.

5. In a steam-engine, the combination, with the main cylinder A and its piston and piston-rod, of the standard F, yoke I, friction-wheel L, cylinders N N' and their pistons, pipes g g', connecting the cylinders N N' with opposite ends of the main cylinder A, and the tappet R, valve-rod S, provided with collars k k', the lever T, and slide-valve C, substantially as specified.
